MATERIAL FEEDING MECHANISM

Erik W. Mikaelson, Easton, Pa., assignor to
Treadwell Engineering Company, Easton, Pa.,
a corporation of Pennsylvania

Application April 5, 1932, Serial No. 603,375

13 Claims. (Cl. 164—68)

This invention relates to feeding mechanism and more particularly to devices of this designation which are adapted to feed material to metal working machines at a controlled rate of speed.

5 The general object of the invention is to provide a novel and improved feeding device for metal working machines.

A more particular object is the provision of a feeding device for metal working machines or the 10 like, in connection with which means are provided for varying the speed thereof in definite relatively large increments, and further means are provided for obtaining a much finer adjustment of speed between the speeds afforded by the coarse 15 adjustments of the first named means, the latter means being adapted to be operated by the metal working machine itself.

20 A further object of the invention is to provide, in connection with a device of this type adapted to feed material to a metal working machine having a predetermined cycle of operation, means for varying the speed of the feeding device by definite 25 relatively large increments, and further means for varying the speed of the feeding device during a portion only of the cycle of operation of the metal working machine to obtain a much finer 30 adjustment of the feed of material during a given cycle of operation.

35 In its preferred embodiment, the invention contemplates the provision of a feeding device for a flying shear of the type disclosed in my copending application Serial No. 530,989, filed April 17, 1931, in which the speed of rotation of the shear knives varies during portions of their cycle of movement 40 in order to synchronize the linear speed of the knives and the material at the moment of cutting, although it is obvious that the principles thereof may be embodied in an arrangement for feeding a definite fixed length of material to any 45 machine during a predetermined cycle of movement of that machine and for varying said length in very small and definite increments.

50 In the exemplary embodiment illustrated, an ordinary change speed gear box is interposed between the feeding mechanism and the common driving means for the feeding mechanism and the shear, for obtaining a rough adjustment of the speed of the feeding means, which may provide for variations in the length of material cut in increments of about two feet. Also positioned 55 between the feeding mechanism and the driving means is a differential mechanism which is operatively connected with one of the rotating shafts of the shear knives, whereby, during a portion of the rotation thereof, the speed of the feeding

mechanism may be increased by smaller amounts to vary the length of material cut by finer increments, such as, for example, as small as $\frac{1}{16}$ or $\frac{1}{32}$ of an inch, between the limits of adjustment of the gear box.

60 Thus the feeding mechanism may be adjusted to operate rapidly through a portion of the interval between cuts by the shear and more slowly during the time the knives are engaged with the material, this slower speed being, in the case of the shear illustrated, the linear speed at which the knives and the material are adapted to move in substantial synchronism. This synchronism between the linear speed of the knives and material being fed is obtained in the manner fully 65 described in my copending application and will 70 be referred to hereinafter.

75 It has been found that it is good practice to adjust the shear knives so that, at the moment of making a cut, they will be running slightly slower than the feeding device in order to preclude the possibility of their pulling or exerting a tension on the material. This will permit a very slight excess of material to be fed during the actual cutting time and will result in the formation of a 80 slight buckle in the strip. To allow for this buckle, the invention contemplates the provision of a main feeding device located at some distance from the flying shear and an auxiliary feeding 85 device disposed as closely as practicable to the shear and adapted to be brought into operation at least by the time the tail end of the strip of material has left the main feeding mechanism.

90 Further objects and features of novelty will be apparent to one skilled in the art upon a consideration of the following specification when taken in connection with the accompanying drawings in which one embodiment of my invention is 95 illustrated by way of example.

In the drawings:

Figure 1 is a plan view of a flying shear and feeding mechanism therefor which comprises a preferred embodiment of my invention;

Figure 2 is a vertical cross-sectional view taken 100 on the line 2—2 of Figure 1;

Figure 3 is an end view of the gear box included in the means for obtaining the coarse adjustment of the feeding speed;

Figure 4 is a vertical cross-sectional view taken 105 on the line 4—4 of Figure 1;

Figure 5 is a view in side elevation of the shear end of the installation;

Figure 6 is a detailed cross-sectional view illustrating the driving pawl mechanism for effecting 110

the differential drive, and taken on line 6—6 of Figure 1; and

Figure 7 is a similar view of the holding pawl mechanism taken on line 7—7 of Figure 1.

5 Referring to Figures 1 and 5 of the drawings, the numeral 10 designates generally a flying shear of the type disclosed in my copending application Serial No. 530,989, to which reference is made for a complete detailed description of the construction and operation of the shear and its control mechanism. For the purposes of the present specification, a brief description of this arrangement will suffice.

15 The upper and lower shear knives 11 and 12, respectively, which carry cutting blades 13 and 14, are mounted in the housing or pedestal 18 for rotation in unison upon the upper and lower shafts 15 and 16, respectively. Outside of the shear frame or housing 18, the upper and lower 20 shafts 15 and 16 are provided with intermeshing gears, the upper one of which is shown at 20. Further along, the upper shaft 15 is provided with a device, generally indicated by the numeral 22, for changing the phase of rotation of the shaft 15 25 with respect to the aligned shaft 23, from which shaft 15 receives its driving force. A housing 25 is splined to the end of the shaft 23, and a worm wheel 26, enclosed within the housing 25, is keyed to the end portion of the shaft 15. An extension 30 27 of the housing 25 is provided with bearings for a worm shaft 28 provided with the worm 29 which is adapted to mesh with the worm wheel 26. It will be readily understood that, by manipulation of the worm 29 by means of a suitable tool 35 applied to the squared end of the shaft 23, the shafts 15 and 23 may be offset from each other by a definite predetermined angular extent for a purpose which will be hereinafter explained.

Shaft 23, supported in the bearings 31 provided 40 on a suitable base 32, is adapted to carry upon its end opposite to that which is operatively connected to the shaft 15, a counterbalanced crank 35. With this crank 35 is adapted to be operatively connected another counterbalanced crank 45 36 which is fixed on the end of a driving shaft 37. A crank pin 38 carried by the end of the crank 36 is adapted to carry a slide block 39 which is adapted to move back and forth in the slot 40 provided in the crank 35. It will be noted that the 50 axes of drive shaft 37 and of shaft 23 are out of alignment, and it will be readily understood that, by means of the sliding crank connection just described, although shaft 37 is adapted to rotate at uniform angular velocity, the shaft 23 will be given a non-uniform motion. In other words, 55 during a portion of a single rotation of shaft 23, it will be moving more slowly than during the remainder of the rotation, and it will also be apparent that by means of the device 22 the angular velocity of the shaft 15, and consequently 60 of the shear knives 11 and 12 at the time of taking a cut, may be varied between certain maximum and minimum speeds for a given speed of the driving motor.

65 Drive shaft 37 is adapted to be operated by the motor 42 through the shaft 43 and gearing 44, 45, 46, and 47, this transmission means being mounted in the frame 50 as clearly shown in Figure 1. It will be understood that, by means of the mechanism just described, the linear speed of the shear blades 13 and 14 may be synchronized with the speed of the material being fed to the shear during the actual cutting operation without changing the general speed of the flying shear in revolutions per minute.

The flying shear is provided with a delivery table 55, and a feed table 56 which is adapted to extend from the main feed roll stand 57 to a point in close proximity to the shear. A short table 58 is provided for supporting the material in advance of the feeding mechanism as it is delivered from the roller table 59.

80 Within the purview of the present invention, any suitable type of feeding mechanism may be employed such as a roller-leveler or straightener or the like, but in the preferred embodiment which is illustrated in the drawings, there is shown a feed roller device comprising the lower roller 60, which is carried in bearings provided in the stand 57, and the upper roller 61 which in operation is adapted to bear downwardly upon the strip of material to be fed. The roller 61 is provided with trunnions or an axle which is rotatably carried upon the end of the lever arms 62, one of which forms a part of the bell crank lever 63, fulcrumed at the ends of the shaft 64 which is carried by the stand or support 57. The vertical arm 66 of the bell crank lever 63 is bifurcated at its lower end as at 67, and the bifurcations are adapted to straddle the rod 68 upon which is carried the coil spring 69 for urging the arm 66 rearwardly and thus causing the roller 61 carried in the upper arms 62 to bear resiliently downwardly upon the material being advanced.

90 Since, in practice, it is sometimes desirable to have the material advanced to the shear at a rate of speed which is very slightly greater than the linear speed of the blades at the time of making the cut so as to cause the strip of material to buckle slightly, the main feeding rollers mounted in the stand 57 are disposed at a considerable distance from the shear, and consequently when the tail end of the strip of material has passed these rolls, there will be nothing but the momentum of the material to continue its movement, 100 and since this momentum would gradually decrease, an irregularity in the length of the last piece cut from the strip would result. To obviate this difficulty, an auxiliary roll stand 70 is provided which includes the lower roll 71, the upper roll 72, and the levers 73. For transmitting the driving force to the auxiliary feed rollers, beveled gears 74 and 75 are mounted upon the ends of the lower roller axles and are adapted to mesh respectively with the beveled gears 76 and 77 which are carried upon the ends of the longitudinal shaft 78 which is adapted to rotate in the bearings 79 and 80 carried by the stands 57 and 70 respectively.

105 It will be noted that, since the auxiliary feeding device mounted in the stand 70 is normally out of operation, the compression spring 82 carried by the rod 83 which is pivoted to the lower arm 84 of the bell crank 73 is arranged to urge the roller 72 in a direction away from the strip of material, while the arrangement in the case of the main feeding device, as has already been described, is designed to maintain these rollers in operative feeding position. As a means for releasing the main feeding device from operation by raising the roller 61 and for simultaneously causing the roller 72 of the auxiliary device to engage the material, there is provided the cylinder and piston devices 90 and 91, the piston rod 92 of the device 90 being connected 115 by means of the link 93 to the lower arm of one of the bell crank levers 63, and the piston rod 95 of the device 91 being connected by means of the link 96 to a rearwardly extending arm 97 formed upon one of the bell crank levers 73 of 120 125 130 135 140 145 150

the auxiliary feeding device. It will be readily understood that an outward movement of the piston rods 92 and 95 effected by the admission meters 130, 131, and 132 which may be of equal diameter, will cause the disengagement of the main feeding device and the engagement of the auxiliary one. The admission of pressure fluid to the cylinders 90 and 91 may be effected by any suitable means such as compressed air to the pistons 92 and 95. At the proper ends thereof, idler gears 133, 134, 135, and 136 which are so mounted on the two shafts 103 and 108, will be selectively engaged with their corresponding gears carried by the brackets (not shown) there are provided the cylinders 90 and 91. The rotation of the input shaft 103 will be imparted to the output shaft 108 in the proper ratio to obtain the basic operating speed of the feeding mechanism which is next below the exact speed required for the desired length of cut of the material. In case the finger 250 is employed, it is adapted to open the contacts 251, as shown in Figure 5, and break the electrical circuit between the battery 252 and the solenoid 253. The solenoid 253 is designed to operate the valve means 254 for controlling the admission and exhaust of fluid pressure to the cylinders 90 and 91. When the solenoid 253 is de-energized the piston 255 of the controlling valve is in the position illustrated wherein fluid pressure is exhausted from the cylinders 90, 91, through the piping 256 by means of the passageway 257 in the valve 255. When the tail end of the strip of material 260 has passed the finger 250 the contacts 251 are closed, energizing the solenoid 253, raising the valve body 255 and causing the valve passageway 261 to permit admission of fluid pressure to the piping 256 which will then release the feed roller 61 from the material and cause the feed roller 72 to engage it at a point nearer the shear. Any other suitable mechanism may be substituted for the fluid pressure device 253 closed within the scope of the appended claims.

For driving the feed rollers, any suitable source of power may be employed, but, for the purposes of obtaining a better synchronization between the feeding means and the flying shear, it is preferred to use the same source of power, such as the motor 42, for driving both of these instrumentalities. For this purpose a shaft 100 is coupled to the opposite end of the shaft 43 from the motor 42 and is adapted to drive the shaft 101 through the beveled gearing indicated at 102. The shaft 101 is operatively connected to the input shaft 103 of the change speed gear assembly indicated generally by the numeral 105, by means of the beveled gears 106. The output shaft 108 of the change speed assembly is coupled with the input shaft 109 of the differential transmission device indicated generally by the numeral 110, and the output shaft 111 of the differential device is adapted to be connected to the shaft 112 which drives the roller 60 of the main feeding device by means of the cooperating clutch members 115 and 116, the last named member being urged into engagement with the clutch member 115 by means of the coiled spring 117. The clutch is adapted to be disengaged by means of the fluid pressure device 120, the piston 121 of which is adapted to be connected with the bifurcated clutch operating arm 122 by means of the link 123.

By means of the change speed gearing 105, a coarse adjustment of the speed of the feeding mechanism may be obtained whereby the length of cut of the material may be varied in increments of, for example, two feet. For this purpose there are secured to the input shaft 103 of this unit the gears 125, 126, 127, and 128 of successively decreasing diameters. In this embodiment only four of these gears are shown, but it will be readily understood that any practicable number may be used. On the output shaft 108

obtaining a finer adjustment of the speed of the feeding mechanism so that the length of the material cut may be varied by much smaller increments than the two foot intervals afforded by the change speed assembly 105, and as will be understood from the following description, these further finer variations in feeding speed are obtained by speeding up the feed rollers during only a portion of the cycle of rotation of the knives of the flying shear 10. More specifically, the increased speed of the device to secure the secondary adjustment is accomplished during a portion of the rotation of the blades when they are not engaged in cutting a strip of material. In this manner, the basic speed may be adjusted at the nearest two foot interval below the desired exact speed by means of the change speed gearing 105, and by adjusting the device 22, the linear speed of the shear knives at the moment of making a cut may be brought into substantial synchronism with this basic speed. Then the speed of feeding during a portion of the rotation of the knives, when they are out of contact with the material, may be increased in order to obtain the exact desired length of cut without interfering with the synchronism which is necessary during the actual cutting operation.

This means for obtaining the fine adjustment of the feeding speed will now be described. Upon the inner end of the input shaft 109 of the differential device 110 is secured the beveled gear 140, and the inner end of the output shaft 111 carries the beveled gear 141. Planetary or idler gears 142 and 143 carried by the stub shafts 144 and 145 are adapted to mesh with the beveled gears 140 and 141. The shafts 144 and 145 are rotatably mounted in bearings carried by the planet carrier or body portion 150 of the differential 110. When this body portion 150 is stationary, it will be seen that the output shaft 111 will rotate in a direction opposite to that of the input shaft 109, and at the same speed, which is, of course, determined by the setting of the change speed arrangement 105. It will also be understood that rotation of the body member 150 of the differential in the same direction as the direction of rotation of the output shaft 111 will increase the speed of the output shaft and therefore of the feed rollers at 57. Therefore, finer gradations of the speed of feeding within the two foot intervals afforded by the change speed gearing may readily be obtained by the proper amount of movement, during a given cycle of operation of the shear, applied to this body member 150, and it is preferred in the present embodiment to move the body member 150 in one direction only, namely, that by which

the speed of the output shaft 111 and the feed rollers may be increased from a basic speed corresponding to the setting on the change speed assembly. This movement of the member 150 is

accomplished by means of the following mechanism.

Upon the extended outer end of the lower shear knife shaft 16 is fixed the counterbalanced crank arm 160. This crank arm 160 is provided with a slot 161 and the counterweighted portion 162. A block 165 is adjustably disposed in the slot 161 and is adapted to receive a pivot pin 166 for the connecting rod 167, the other end of which is pivotally connected as at 168 with the lever arm 169 which is secured to the rock shaft 170. The rock shaft 170 is rotatably mounted in the bearings 172 and 173 which are mounted in suitable supporting frames 174 and 175. The shaft 170 is preferably disposed in parallel relation to the input and output shafts of the differential device 110 and at a suitable point, preferably opposite the input shaft 109, a gear sector 180 is secured upon the rock shaft 170.

By referring particularly to Figure 4 of the drawings, it will be seen that the body portion 150 of the differential mechanism 110 is provided with a sleeve-like extension 182 which is adapted to surround the input shaft 109 and in which the latter shaft is adapted to rotate. Bearing bushings 183 and 184 are provided at the points of frictional contact between the shaft 109 and the sleeve 182. The sleeve 182 is mounted for rotation in the bearings 185 which are carried by one of the uprights 186 of the differential frame 187. A gear or pinion 190 is mounted for rotation upon the sleeve 182 and is provided with the bushing 191. Keyed to an extension 192 of the gear 190 is the ratchet arm 195 which is adapted to carry, by means of a pivot pin 196, the two ratchets or pawls 197 and 198 which are adapted to engage with the ratchet teeth 199 formed on the ratchet wheel 200, which is rigidly supported by the differential body member 150. Each of the pawls 197 and 198 is provided with rearward extensions 202 which are in turn provided with rods 203 which are adapted to pass through the upper overturned portion 204 of the ratchet arm 195 and the pawls are adapted to be urged toward engagement with the ratchet teeth by means of the coil spring 205. The gear sector 180 is adapted to mesh with the gear 190 and upon each downward oscillation thereof, caused by the rotation of the crank arm 160 carried by the shear knife shaft 16, will move the gear 190 and the ratchet arm 195 in a clockwise direction, as viewed in Figure 6. Then, by means of the ratchet and pawl device, this movement will cause the body member 150 of the differential to move a predetermined degree in the same direction of rotation as the output shaft 111.

During the upward movement of the sector 180 when the crank pin 166 is moving through the lower half of its orbit, the gear 190 and the ratchet arm 195 will move in a counterclockwise direction, as seen in Figure 6, and the pawls 197, 198 will click idly over the ratchet teeth 199. In order to prevent the body 150 of the differential from rotating, during this reverse movement of the actuating mechanism, due to the reaction of the load and the friction of the bearings thereof, the following mechanism is provided. Another sleeve-like extension 210 is provided for the body member 150 and this extension is adapted to surround the output shaft 111 which is adapted to rotate in suitable bearing bushings 211 and 212. The sleeve 210 is mounted in a bearing 214 which is carried by the upright 215 of the differential frame 187. A ratchet wheel 217 is secured to the extension 210 and is provided with teeth 218

which are adapted to be engaged by the holding pawls 219 and 220 suitably supported by the pedestal 221 and adapted to be urged into engagement with the teeth by means of the springs 222, all of which is clearly shown in Figures 2, 4 and 7.

In order to regulate the extent of movement of the sector 180, and thus of the body portion 150 of the differential 110, means are provided for adjustably securing the pivot block 165 at different distances from the center of rotation of the crank arm 160. As stated heretofore, the block 165 is adapted to slide in the slot 161 formed in the crank arm, and it is also provided with a threaded opening therethrough through which the threaded shaft 225 is adapted to extend. The ends of the shaft 225 are rotatably supported in the end walls of the slot 161 and the shaft is capable of being rotated by the application of a suitable tool to the squared end 227 thereof. A lock nut 228 or other suitable means is provided for retaining the shaft in proper adjusted position. It will be readily understood that, upon rotation of the shaft 225, the block 165 may be moved along the slot 161 to the proper position to obtain the desired throw of the sector 180. It is obvious that when the pivot pin 166 is axially aligned with the shaft 16 there will be no movement of the connecting rod 167 nor of the sector 180 and the speed of the feeding rollers will be exactly that given by the adjustment of the change speed gear assembly 105. When the block 165 is positioned at the outermost limit of its movement, as illustrated in Figure 5 of the drawings, the sector 180 and the ratchet arm 195 will then move through their maximum arcs, and it is preferred that this degree of movement be sufficient to speed up the feeding device during one cycle of operation of the shear an amount equal to the interval between the adjustments of the speed change gearing 105. If the circumferences of the feed rolls 60, 61 are two feet, then this maximum degree of additional movement afforded by the differential device may cause one additional revolution of the feed rollers during a single revolution of the shear knives and will, of course, cause an increase of two feet in the length of material cut. One edge of the slot 161 may be graduated as at 230 in very small intervals representing, say, $\frac{1}{16}$ or $\frac{1}{8}$ of an inch increments in the length of material cut, and the device may be very readily adjusted to effect these variations in the length of cut by setting a mark in the block 165 opposite the desired graduation in the scale 230.

From an inspection of Figure 5 of the drawings, it will be seen that the relation of the crank arm 160 and the shear knives 11 and 12 is such that, during the effective rotation of the crank arm 160 through the upper half of its circle of movement, the knife 12 will be moving from its lowermost position to its uppermost position where it is adapted to cooperate with the upper knife 11 to make a cut. By means of this arrangement, the speeding up of the device to provide for the additional length of cut over the basic setting of the change speed gear 105 takes place during the last half of the cycle of movement of the shear knives and that the feeding rollers have returned to their basic speed with which the linear cutting speed of the knives has been synchronized at the time the cut is made. Therefore, it will be apparent, that this fine adjustment of the length of material cut cannot interfere with the adjustment of the device 22 by which the speed of the

knives at the moment of cut is substantially synchronized with the speed of the material at that instant. Any fixed phase relation of the crank arm 160 and the shear knife 12 may exist for the purposes of this invention, which will ensure that no movement of the differential planet carrier 150 takes place during the time the shear knives are making a cut.

The ratchet teeth 199 and 218 in the wheels 200 and 217 are as closely spaced as practicable so that the amount of rotation may be governed within very small degrees, and the provision of multiple pawls of different lengths as has been described will be effective to further subdivide these divisions. A practicable example will further illustrate the operation of this entire arrangement.

Let it be assumed that the orbit of the shear knives is 15 feet in circumference, that the shaft carrying the driving crank is rotating at the rate of 30 revolutions per minute and that the proportion and relative locations of the driving crank and the driven crank are such that the momentary linear velocity of the shear knives varies during one complete revolution, between the limits of a maximum rate of 600 feet per minute and a minimum rate of 300 feet per minute with a mean rate of 450 feet per minute. It is also assumed that by means of the worm and worm wheel adjustment between the variable speed mechanism and the shear, the point at which the shear knives come into cutting position has been so located, that their velocity at that time corresponds properly with that of the material. If the gear ratio between the shear and the driving motor is 1 to 10, the motor will be operating at 300 revolutions per minute, and this will also be the speed of the input shaft 103 of the change speed gearing 105. Then, if it is assumed that the ratios of the four sets of change speed gears in the assembly 105 is 10 to 10, 9 to 10, 8 to 10, and 7 to 10, the output shaft 108 may be adjusted to rotate at the rates of 300, 270, 240 or 210 R. P. M. The ratio of the speed of the input shaft 109 of the differential 110 to the output shaft 111 thereof, when the planet carrier 150 is stationary, is 1 to 1. Therefore the speeds of the feed rollers, operatively connected to the output shaft 111, which are obtainable by adjustment of the change speed gearing 105, are 300, 270, 240 or 210 R. P. M. This will give feeding speeds of 600, 540, 450 or 420 feet per minute, respectively; and, since the shear makes 30 cuts per minute, the lengths of cut obtainable by means of the adjustment of the change speed gear 105 are 20, 18, 16 and 14 feet, respectively. If the desired length of cut is, for example, somewhere between 18 and 20 feet, those gears in the change speed gear box 105 will be engaged which will give the 9 to 10 ratio, and the proper setting to obtain the additional length required will be made by the sliding block 165 in the crank arm 160. The obtaining of this latter fine adjustment will be clear from the following explanation.

Assuming that the feed rollers are two feet in circumference and that the ratchet wheels are, say, 96 inches in circumference and are provided with 384 teeth spaced at one quarter inch intervals, each tooth advanced will be 24 inches divided by 384, or $\frac{1}{16}$ of an inch. With two pawls arranged in staggered relation, the feed may be advanced in intervals of one half of the width of a tooth or $\frac{1}{8}$ of an inch of the actual length of material fed. The segment 180 is preferably of sufficient angular extent to give one complete turn

to the body 150 of the differential, which, of course, will effect a complete additional revolution of the feed rollers 60 and 61. This, of course, increases the total increment of feeding to the point where the next higher gear ratio of 80 the device 105 will be used, starting with the differential body held stationary. Intermediate settings of the block 165 will give any length desired within the two foot intervals.

It will be apparent that the present invention may be applied to other apparatus than the flying shear illustrated in the exemplary embodiment. It will also be understood that various changes and modifications may be made in this embodiment without departing from the scope of the invention as illustrated in the following claims.

Having thus described the invention, what is claimed as new and desired to be secured by Letters Patent is:

1. In a device of the class described, in combination, a metal working machine, continuously operating feeding mechanism by means of which material may be fed to said machine at a predetermined rate, driving means for said feeding mechanism, transmission means operatively connecting said driving means and said feeding mechanism, means for positively applying a coarse adjustment to said transmission mechanism independently of the other elements of the device for regulating the rate of feeding by definite increments, and separate means actuated by said metal working machine and operatively connected with said transmission means for regulating said rate of feeding in response to a fine adjustment.

2. In a device of the class described, in combination, a metal working machine adapted to perform successive predetermined cycles of operation, continuously operating feeding mechanism by means of which material may be fed to said machine at a predetermined rate, driving means for said feeding mechanism, transmission means operatively disposed between said driving means and said feeding mechanism, means for positively applying a coarse adjustment to said transmission mechanism independently of the other elements of said device for regulating the rate of feeding by definite increments, and means actuated by said metal working machine and operatively connected with said transmission means for regulating said rate of feeding in response to a fine adjustment, said last named means being operative only during a portion of said cycle of operation.

3. In a device of the class described, in combination, a metal working machine, feeding mechanism by means of which material may be fed to said machine at a predetermined rate, common driving means for said machine and said feeding mechanism, transmission mechanism disposed between said driving means and said feeding mechanism and including a change speed gear for controlling said rate of feeding, and a differential device, means for positively applying a coarse adjustment to said change speed gear independently of the other elements of the machine, means driven directly by said metal working machine and adapted to affect said differential device to control said rate of feeding in accordance with a fine adjustment.

4. In a device of the class described, in combination, a metal working machine adapted to perform successive predetermined cycles of operation, feeding mechanism by means of which

- material may be fed to said machine at a pre-determined rate, common driving means for said machine and said feeding mechanism, transmission mechanism disposed between said driving means and said feeding mechanism and including a change speed gear for controlling said rate of feeding in response to a coarse adjustment and, a differential device, means actuated by said metal working machine and adapted to affect 5 said differential device to control said rate of feeding in accordance with a fine adjustment, and means operatively disposed between said driving means and said metal working machine for affecting said cycles of operation, said last named feed controlling means being operative only during a portion of each cycle of operation.
5. In a device of the class described, in combination, a metal working machine adapted to perform successive predetermined cycles of operation, feeding mechanism by means of which material may be fed to said machine at a predetermined rate, driving means for said feeding mechanism, change speed gearing operatively disposed between said driving means and said feeding mechanism for controlling the rate of feed of said feeding mechanism in response to a coarse adjustment, planetary gearing also disposed between said driving means and said feeding mechanism, means connected to the planet carrier of said gearing and operatively connected with said metal working machine and adapted to be driven thereby during a portion of its cycle of operation to move said carrier to effect a change in said feeding rate in response to a fine adjustment, and means for adjusting said last named means.
6. In a device of the class described, in combination, a flying shear, feed rolls by means of which a strip of material may be fed to said shear at predetermined rates to control the lengths into which said strip is cut, driving means for said feed rolls, a change speed gear disposed between said driving means and said rolls for varying the linear speed of said rolls and thus the lengths of cut by definite increments, means for positively adjusting said change speed gear independently of the other elements of said device and separate change speed means also disposed between said driving means and said rolls and actuated by said shear for varying said speed and length of cut by smaller increments.
7. In a device of the class described, in combination, a flying shear provided with a shear blade, means for feeding material to said shear, means for adjusting the operation of said shear and said feeding means so as to synchronize the linear speeds of said blade and of the material being fed at the moment of taking a cut, and means for varying the speed of said feeding means operable only during intervals between successive cuts by said shear, whereby the rate of feed and consequently the length of cut may be varied without affecting the synchronism of said shear and feeding means during said cuts.
8. In a device of the class described, in combination, a flying shear provided with a shear blade, means for feeding material to said shear, means for adjusting the operation of said shear and said feeding means so as to synchronize the linear speeds of said blade and of the material being fed at the moment of taking a cut, means for adjusting the speed of said feeding means in definite steps to vary the length of cut by coarse increments, means for increasing the speed of
- said feeding means from one of said steps to another or to an intermediate rate of feed, said rate increasing means operable to change the speed of said feeding means only during intervals between successive cuts by said shear.
9. In a device of the class described, in combination, a metal working machine, feeding mechanism by means of which material may be fed to said machine, driving means for said feeding mechanism, a differential device comprising planetary gearing operatively disposed between said driving means and said feeding mechanism, a pawl and ratchet device associated with the planet carrier of said gearing, a crank arm adapted to be driven by said metal working machine, a connecting rod adjustably connected with said crank arm, gearing operatively disposed between said crank arm and said pawl and ratchet device, said device adapted to be actuated to move said planet carrier in one direction only to increase the speed of said feeding mechanism, and means for adjusting the connection between the crank arm and said connecting rod for obtaining the desired increased speed.
10. In a device of the class described, in combination, a metal working machine, a device for feeding material to said machine at predetermined rates, said device comprising feed rollers disposed at a considerable distance from said metal working machine, which is greater than the minimum length of material to be fed, auxiliary feed rollers disposed in close proximity to said machine, and means for bringing said feed rollers into engagement with said material in alternation.
11. In a device of the class described, in combination, a flying shear and means for feeding material to said shear at predetermined speeds to control the length of cut of said material, said feeding means comprising feed rollers disposed at a considerable distance from said shear, additional feed rollers disposed in close proximity to said shear and means for disengaging said first named feed rollers and for simultaneously bringing said second named feed rollers into engagement with the strip of material being fed, as the tail end of said strip passes a predetermined point.
12. In a device of the class described, in combination, a flying shear, feeding mechanism by means of which a strip of material may be fed to said shear, driving means for said feeding mechanism including a change speed device for adjusting the speed of said feeding mechanism at predetermined basic rates of feed, whereby the lengths into which said strip is cut may be varied by definite coarse increments, driving means for said shear including a device for synchronizing the speed of said shear with that of said feeding mechanism at the time a cut is being made without changing the average speed of said shear, means operatively connected with the drive for said feeding mechanism for changing the basic speed of said feeding means to alter the length of cut by finer increments, and means controlled by said shear for operating said last named means only during a portion of the interval between cuts.
13. In a device of the class described, in combination, a metal working machine, feeding mechanism by means of which material may be fed to said machine at a predetermined rate, driving means for said feeding mechanism, change speed gearing operatively disposed between said driving means and said feeding mechanism for controlling the rate of feed of said feeding mechanism in response to a coarse adjustment, means for

positively applying such coarse adjustment to said change speed gearing independently of the other elements of the device, planetary gearing also disposed between said driving means and said feeding mechanism, a mechanical driving connection between said metal working machine and the planet carrier of said planetary gearing, said driv-

ing connection acting solely in response to the operation of said metal working machine to move said carrier to effect a change in said feeding rate in response to a fine adjustment, and means for adjusting the amount of movement of said driving connection.

ERIK W. MIKAELSON.
